UNITED STATES PATENT OFFICE.

PETER G. RINKEN, OF CHICAGO, ILLINOIS.

DESIGN FOR A TABLE-PIECE FOR HOLDING FLOWERS.

51,081.

Specification for Design.

Patented July 24, 1917.

Application filed April 21, 1917. Serial No. 163,718. Term of patent 7 years.

To all whom it may concern:

Be it known that I, PETER G. RINKEN, a citizen of the United States, residing in Chicago, in the county of Cook and State of Illinois, have invented a certain new, original, and ornamental Design for Table-Pieces for Holding Flowers, of which the following is a specification, reference being had to the accompanying drawing, forming part hereof.

Figure 1 is a top plan view of a table piece showing my new design; and

Fig. 2 is a side elevation of the device shown in Fig. 1.

I claim:

The ornamental design for a table piece for holding flowers as shown.

PETER G. RINKEN.
